UNITED STATES PATENT OFFICE.

MICHELE J. BOTTINELLI, OF KELLOGG, IDAHO.

SAFETY DEVICE.

1,139,839.

Specification of Letters Patent.

Patented May 18, 1915.

Application filed April 9, 1914. Serial No. 830,674.

To all whom it may concern:

Be it known that I, MICHELE J. BOTTINELLI, a citizen of the United States, residing at Kellogg, in the county of Shoshone and State of Idaho, have invented new and useful Improvements in Safety Devices, of which the following is a specification.

This invention relates to a safety device.

The purpose of the present invention is to produce a simple, substantial, and cheaply manufactured safety device, which is constructed with the object in view of averting such accidents as are liable to occur in connection with the breaking of cables in mines, or the parting of belts in machine shops when the lacing gives way. The breaking of a cable is generally preceded by the wearing away or breaking of one or more of the strands of which it is composed, and the parting of a belt is similarly preceded by a weakening or parting of the lacing which, if taken in time, would prevent the final break and accidents that are liable to take place in connection with same.

An object of the present invention is to provide a safety device which is capable of detecting any flaw in the cable or belt and give an audible or visible sign in connection therewith. The operator will thus be warned in sufficient time to shut down and make the necessary repairs.

Other objects will hereinafter appear.

The invention consists of the parts and the construction and combination of parts as hereinafter more fully described and claimed, having reference to the accompanying drawings, in which—

Figure 1 is a side elevation, showing the application of the invention. Fig. 2 is an enlarged view of the releasing device. Fig. 3 is a diagrammatic view, showing the electrical circuit controlled by the safety device.

Referring to the drawings, A indicates a pulley; B a belt; and C the safety device, as applied. The safety device in general consists of a lever 2, pivotally mounted, as at 3, in a suitable frame or standard 4. Secured in one end of the lever is a feeler rod 5, composed of a short length of thin wire, and formed on the opposite end of the lever is a hook-like projection 6 which is adapted to interlock with a notch 7 formed in a pulley 8 which is journaled, as at 9, in the upper end of the standard 4. The standard in this instance is represented by a pipe or tube which is carried by an electric switch,

indicated at D. This switch consists of a base 10, upon which is mounted a pair of fiber plates 11 and 12, and interposed between said plates is a glass tube 13, said plates, tube, and base being secured together by bolts 14.

Secured to plate 11, interior of tube 13, is a pair of spring contact members 15, and suspended by a cord 16, secured to the pulley 8, is a tube 17, through the lower end of which projects a pointed carbon rod 18. The tube is otherwise filled with a heavy material, such as lead or the like, indicated at 19, to give it sufficient weight, when released, to force the carbon point 18 in between the points of the spring members 15 to close a circuit through same.

Fig. 3 is a diagram showing the position of the switch D in the electrical circuit controlled by same. This circuit can be traced as follows: 20 indicates a battery, or other suitable source of electric supply, 21 indicates the outgoing wire, and 22 indicates the return; a suitable form of signaling device 23, such as a bell, light or other device, being connected on wire 22. Switch D is connected through wires 24 and 25 with the main circuit wires 21 and 22 respectively and is, therefore, adapted to close a circuit through said wires, when short circuited by carbon 18. A circuit thus closed will either ring the bell, when such a device is used, display a visible signal, or perform other duties for which it may be intended. A suitable number of switches, such as indicated at 26, may also be placed in a circuit and the purpose and operation will be later described.

The operation of the safety device, together with switch D controlled by same, will be as follows: The moment a rope begins to weaken, or a belt lacing begins to give way, it can easily be seen that an end of a broken strand or the end of the lacing will strike the feeler, indicated at 5. This, being very sensitive, will immediately raise a slight distance in the direction of arrow a and will consequently pull the hook 6 out of engagement with the notch 7 in pulley 8. The pulley thus released will be free to turn and will consequently permit carbon 18 to drop down into engagement with the spring contact 15, thus closing the circuit through wires 24 and 25 which connect with the main circuit wires 21 and 22. A circuit is thus established through battery, or any

other source of supply, causing an alarm to be given either by a bell 23, or any other device, which may be controlled by said circuit. For instance, where an electric 5 motor drive is used in a machine shop, as indicated at 30, it would be possible to connect switch D in circuit with a magnet 31, or like device, which could be connected with the trip switch 32 on the main circuit. The closing of the circuit through 10 switch D would in that instance actuate the trip switch and immediately stop the motor. The operator will thus immediately know that a strand has parted, or that the belt 15 lacing is beginning to give way and will thus be given opportunity to make the necessary repairs.

The feeler arm, indicated at 5, can be placed in very close proximity to the face of 20 a rope transmission or a belt and the arm can in all instances be sufficiently long to cover the face of the belt or transmission. The safety device, with connected switch, may be placed practically in any position as 25 it is only necessary to lengthen or shorten the standard 4 to suit various conditions of height.

A suitable number of switches, such as indicated at 26, may also be placed on the 30 main circuit indicated at 21 and 22. These are particularly useful where an electric motor drive is used and controlled by switch D. For instance, in the case where a workman's clothing becomes entangled in a set 35 of gears or where some similar accident should take place it would be very easy for a fellow workman seeing the predicament to close one of these small switches nearest to him. The machinery would thus immediately come to a standstill without the operator running to the motor room to throw out the main switch. Also if a number of men are doing repair work in the 40 plant while it is shut down for repairs, one 45 or more of these switches may be closed, and with any one of these switches closed it will be impossible for anyone to start the motor and kill, or even injure, the men while they are busily engaged with their 50 work.

The materials and finish of the several parts of the safety device are such as the experience and judgment of the manufacturer may dictate.

55 I wish it understood that various changes in form, proportions and minor details of construction may be resorted to within the scope of the appended claims, and that I do not wish to limit myself to the specific design and construction here shown.

Having thus described my invention, what I claim and desire to secure by Letters Patent is—

1. In a safety device, the combination of a standard, an arm pivotally mounted in 65 said standard, a feeler arm secured on one end of the pivoted arm, a hook formed on the other end of the arm, a pulley journaled in the standard having a catch formed thereon with which the hooked end of the arm is 70 adapted to engage, and means controlled by the pulley for closing an electric circuit.

2. In a safety device, the combination of a standard, an arm pivotally mounted in said standard, a feeler arm secured on one end 75 of the pivoted arm, a hook formed on the other end of the arm, a pulley journaled in the standard having a catch formed thereon with which the hooked end of the arm is 80 adapted to engage, a cord secured to the pulley, a weight on the cord, and means controlled by the weight for closing an electric circuit.

3. In a safety device, the combination of a standard, an arm pivotally mounted in 85 said standard, a feeler arm secured on one end of the pivoted arm, a hook formed on the other end of the arm, a pulley journaled in the standard having a catch formed thereon with which the hooked end of the arm is 90 adapted to engage, a cord secured to the pulley, a weight on the cord, a carbon secured on the end of the weight, a pair of flexible contact members with which the carbon is adapted to engage, and an electric 95 circuit controlled by said contact members.

4. In a safety device, the combination of a standard, an arm pivotally mounted in the standard, a feeler arm secured on one end of 100 the standard, a latch engageable with the other end of the arm, and means controlled by said latch when released by the arm for closing an electric circuit.

5. In a safety device, the combination of 105 a standard, an arm pivotally mounted in the standard, a feeler arm secured on one end of the standard, a hook formed on the other end of the arm, a latching member engageable with said hook, and means controlled 110 by said latch when released by the hook for closing an electric circuit.

In testimony whereof I have hereunto set my hand in the presence of two subscribing witnesses.

MICHELE J. BOTTINELLI.
